United States Patent Office.

EVEN KOONS, OF FUNKSTOWN, MARYLAND, ASSIGNOR TO ELIAS EMMERT,
OF WASHINGTON COUNTY, MARYLAND.

Letters Patent No. 60,746, dated January 1, 1867.

IMPROVEMENTS IN TUYERES.

The Schedule referred to in these Letters Patent and making part of the same.

TO ALL WHOM IT MAY CONCERN:

Be it known that I, EVEN KOONS, of Funkstown, in the county of Washington, and State of Maryland, have invented a new and useful improvement in Tuyeres or Fire-Irons; and I do hereby declare that the following is a full and exact description thereof, reference being had to the accompanying drawings, and to the letters of reference marked thereon.

My invention consists in a swinging or hinged plug or valve for regulating the blast through a tuyere or fire-iron, and also in a new arrangement for opening and loosening the box or air-chamber below the tuyere. In the accompanying drawings—

Figure 1 is a top view of my improved tuyere.

Figure 2 is a vertical section of the same.

The general construction of my tuyere or fire-iron may be the same as that already patented by me. But instead of using the conical plug described in that patent, I propose to cast the upper face of the tuyere in one piece, with two sets of openings, A and B, as seen in fig. 1. In the upper part of the air-chamber I have arranged a swinging plug or valve, C, fig. 2, so hinged that it may swing down, as seen in red lines. This valve is moved by means of a jointed wire or rod, D, provided with a knob, H. When the valve is up it closes the outer openings in the face of the tuyere, as seen in fig. 2, whilst the diminished blast passes through the hollow centre C' of the plug, and when down there is a full blast. The cap E is made removable, in order to facilitate the clearing of the air-chamber G of cinders, ashes, and other matter which is liable to fall through the air openings A B. The form of the above-described devices may be somewhat varied without departing from my invention, so long as the result is substantially the same. I do not broadly claim a swinging valve in the air-chamber, but confine my claims to such valve when used to close air-passages in the top of the chamber.

Having thus fully described my invention, what I claim, and desire to secure by Letters Patent of the United States, is—

1. In combination with blast openings in the bed of a forge or furnace, I claim the above-described swinging valve or plug, constructed and operated substantially as set forth.

2. I claim the combination of the cap E, rod D, and hinged valve or plug C, constructed substantially as specified.
